UNITED STATES PATENT OFFICE

JOSEPH J. SCHERMACK, OF JACKSON HEIGHTS, NEW YORK, ASSIGNOR TO AUTOMATIC MERCHANDISING CORPORATION OF AMERICA, A CORPORATION OF DELAWARE

COIN-SELECTING MECHANISM

Application filed January 22, 1929. Serial No. 334,204.

My invention relates to coin detectors or fraud-preventives and particularly to coin detectors associated with check controlled, change-making and like mechanisms; and the 5 general object of the invention is to provide a new and improved fraud preventive or coin detecting or selecting means which shall be highly effective in practical operation.

In practice, it has not been found feasible 10 to use mechanisms heretofore provided making use of a magnetic field or flux to set up eddy currents in a rolling coin for the reason that they require extreme delicacy of adjustment to be effective, and the coin detectors 15 are usually associated with check-controlled or change-making machines which are located in public places and subject to various shocks, jars and vibrations which interfere with the effective operation of the coin detector. In 20 order to make use of the principle in a practical way, I have conceived the idea of associating the magnetic field with a trap door or movable closure so as to insure effective selection.

25 By providing for co-ordinating the effective inclination of the chute with the weight necessary to depress or open the trap door, I am enabled to insure that every coin not designed for operating the change-making, coin 30 vending or other machine with which the detector is associated, will be discarded. In practice, it has been found in using my invention that the nicety of selectivity which it affords will result in discarding or rejecting 35 a coin, say a quarter, one of whose sides has been rubbed so as to reduce only slightly the weight and silver content.

In carrying out the invention, it is preferable 40 to arrange a magnet below the coin chute or runway in advance of the flux field, so as to enable paramagnetic coins to be rejected before reaching field, which may be set up by any suitable means, as by an electro-magnet. When a rolling coin which is dia- 45 magnetic enters said magnetic field, eddy currents will be set up in the coin, in opposition to the magnetic field through which the coin is rolling, and the effect will be to retard or damp the motion of the coin in corre- 50 spondence with these counter currents and to

an extent depending on the materials of which the coin is constituted.

It will be apparent that by varying the inclination of the chute, the speed of the rotating coin may be varied, and also that by 55 varying the weight necessary to depress the trap door or yieldable platform immediately underlying the magnetic field of the electro-magnet, adjustments are afforded which will insure that the desired coin will be retarded 60 or held back momentarily and just sufficiently to operate the trap door, allowing the coin to fall into the operating chute that connects with the associate machine. On the other hand, the eddy currents set up by the 65 non-desired coins will not sufficiently retard them to allow them to operate the trap door but instead they will roll over the trap to an extension of the chute through which they will pass to a rejection receptacle. Preferably 70 the paramagnetic coins under action of the horseshoe magnet will pass through a side chute which also connects with said receptacle.

75 My invention will be described specifically and in detail in connection with the accompanying drawings, wherein

Fig. 1 is a fragmentary elevation, partly in section, of one form of my improved coin detecting mechanism and associate parts; 80

Fig. 2 is a side elevation, partly in section, the view being taken in the general direction of the arrow at the left of Fig. 1;

Fig. 3 is a diagrammatic view of the electric circuit for operating the electro-magnet; and 85

Fig. 4 is a fragmentary view corresponding with the upper part of Fig. 1 but illustrating a modification.

In the Figs. 1-3 construction the general mechanism is shown mounted on the inner 90 face or side of the door 10 of a cabinet 11 of a check controlled mechanism, the door being hinged to the cabinet at 12 and being shown open so as to expose its inner face. The coin detector comprises angularly disposed sec- 95 tions or elements 13 and 14 of a coin chute or runway, the upper section 13 whereof communicates with a circular entrance or coin opening 15 extending through the outer face of the door of the reception of the operating 100

coin. The chutes or sections 13 and 14 are preferably of sheet metal and are rectangular in cross-section, the inner dimensions being adapted to accommodate desired coins, in the 5 present instance, quarter-dollars. The section 13 is suitably mounted on the inner face of the door as by brackets 16 in a set position and preferably, as shown in Fig. 1, enters or is telescoped into the upper end portion of 10 the downwardly inclined section or element 14 of the chute or runway. The inclination of the section 14 being variable, as hereinafter described, it will be seen that the two sections 13 and 14 of the chute are relatively 15 settable. The section or chute 14 extends leftward as seen in Fig. 1, terminating in a downwardly turned end which fits loosely into the upper flaring end portion of a chute extension 17 which extends downward and com- 20 munciates with a receptacle 18 for rejected coins. It may be noted at this point that the chute section 13 is provided with a downwardly extending off-chute or side drop 19 which likewise communicates with the recep- 25 tacle 18.

There is provided a two-part electro-magnet 20 comprising solenoids 21, vertically disposed core pieces 22 and horizontally disposed pole pieces 23 suitably secured to the upper 30 ends of the core pieces. In Fig. 3 is diagrammatically illustrated an electric circuit for the magnet, the positive wire 24 passing through a fuse box 25, the wire 24 connecting with one solenoid; whereas the negative current passes 35 through a fuse box 26 and thence through a rheostat R conventionally illustrated and which connects by a wire 27 with the other solenoid. The electro-magnet is supported on a horizontal bracket 28 which is fixed to the 40 inner face of the door 10, and the pole pieces, as is plain from Fig. 2, project oppositely through the walls of the inclined chute 14 preferably terminating in the planes of the inner faces of said walls. In the neighbor- 45 hood of the core pieces the side walls of the chute 14 are enlarged or embossed as indicated at 29, the enlargements being bored out so as to fit over the pole pieces which thereby provide a support for the chute 14. The en- 50 largements receive set screws 30 whereby the inclination of the chute 14 may be varied, swinging movements to obtain such variations taking place, of course, around the axis of the pole pieces. It will be understood 55 that adjustment of the chute 14 will not affect the other chutes or portions 13 and 17.

Directly below the magnetic field which passes transversely of the chute 14 between the pole pieces, the floor or bottom of the 60 chute is made movable for a portion of its length between its ends. As herein shown the movable portion is in the form of a balanced closure or trap door 31 which fits in an opening 14^a in the bottom of the chute and is provided with a pivot 32 which bears in

parallel extensions or ears 33 that project downward from the lower side of the chute and below its bottom. The pivot 32 is extended rightward as viewed in Fig. 2 and has mounted on it a tail piece 34 on which is slidably supported an adjustable counter-balance or weight 35, the weight having a spring clip 36 which is effective to maintain it in adjusted positions. It will be seen that by arranging the tail piece at one side, its path of movement will be unobstructed so that it can swing freely upward to the dotted line position of Fig. 1, thus enabling the closure or door 31 to swing open and freely downward when acted on by a coin of proper weight. The free end portion of said trap door is preferably offset as shown at 31^a so as to provide a stop which contacts with the under face of the chute bottom 14 and prevents the counter-weight 35 from swinging the upper or operative face of the trap door upward above the plane of the bottom of the chute 14.

Normally the entire length of the chute floor is smooth and uninterrupted and the weight 35 of the trap door is so adjusted and co-ordinated with the inclination of the chute 14 that the eddy currents set up in non-desired coins rolling down the chute or runway will not sufficiently interrupt their movement as to enable them to depress the trap door and let them through. To operate the trap the coin must fulfill two conditions, namely, it must be both diamagnetic and of a weight corresponding with the setting or adjustment of the coin detecting apparatus. Coins not fulfilling the requirements of weight and fineness will roll on over the trap door and pass down through the chute extension 17 into the rejection receptacle 18. The trap door 31 normally closes the top of a downwardly extending zig-zag or variably curved chute element 37 which communicates eventually with a suitable receptacle or holder. As herein shown, there is interposed between the trap door and the coin holder check controlled mechanism, generally designated by the numeral 38. It will be understood that any coin of proper weight and fineness will depress the closure or trap door 31 and pass downward through the chute 37 so as to become effective to release the check-controlled mechanism enabling it to be operated. Thereafter the effective coin, which has been diagrammatically illustrated in three of its successive positions 39^a, 39^b and 39^c, will pass downward into 115 a suitable coin receptacle within the cabinet 11 and not accessible to the public.

For preliminary withdrawal of paramagnetic coins before the electro-magnet is reached, there may be provided a horse-shoe magnet 40 secured at 41 to the inner face of the door 10 and so related to the off-chute 19 that it will cause steel and iron coins and the like to turn the corner and pass downward through said chute, such a coin being illus- 130

trated in Fig. 1 and designated by the numeral 42.

Thus it will be apparent that only coins diamagnetic in varying degrees will pass the turn connecting the chute elements 13 and 14 and roll freely down the inclined chute 14 until they enter the magnetic field between the pole pieces 23, 23. As has been explained, the mechanism provides practical means, comprising the closure 31 balanced in co-ordination with the inclined chute 14, for insuring that only coins of the weight and fineness for which the mechanism is designed to operate will be effective, which, in the illustrated instance, means will open the trap door and pass down through the operating chute 37 to the associate mechanism 38.

Various changes may be made without departing from the invention, and one modification is illustrated in Fig. 4 which, instead of showing relatively movable coin chute sections, illustrates the coin chute as comprised of sections 43, 44 and 45 which in effect constitute a one-piece sheet metal construction, together with the extensions and off-chutes which correspond with those above described. This one-piece construction is feasible in practice since after repeated experiments have shown the proper relative inclination of the chute elements, they may be rigidly assembled. The opening at 46 may be sufficiently large to communicate properly with the opening 15 in allowance for any shifting or setting.

It will be understood that my invention need not necessarily be employed with mechanism relating to vending, dispensing or change making; and also that various other changes besides those described may be made without departing from the invention.

I claim:—

1. In coin selecting mechanism, the combination of a runway, an electro-magnet having its magnetic field disposed transversely of the runway, and a trap door in the runway underlying the magnetic field and permitting the entrance of coins affected by said field.

2. In coin selecting mechanism, the combination of a runway, and an electro-magnet having its pole pieces so arranged that the magnetic field is disposed transversely of the runway, the floor of the runway having a yieldable portion directly beneath the pole pieces and yielding to permit the passage of coins on which said field has a predetermined effect.

3. In coin selecting mechanism, the combination of a runway, an electro-magnet having its poles so arranged that the magnetic field is disposed transversely of the runway, the floor of the runway having a yieldable portion directly beneath the magnetic field, said yieldable portion being normally maintained in the plane of the floor, and stop devices for preventing movement of said yieldable por-

tion above said plane, said portion yielding to permit the passage of coins on which said field has a predetermined effect.

4. In coin selecting mechanism, the combination of an inclined coin chute, an electro-magnet having its magnetic field disposed transversely of the chute between its ends, means for affording variation in the inclination of the chute, and a yieldable trap door in the floor of the chute directly under the magnetic field and normally maintained in the inclined plane of said floor.

5. In coin selecting mechanism, the combination of a coin chute, an electro-magnet having its magnetic field disposed transversely of the chute, and a trap door pivotally mounted on the chute and having its contact face normally in the plane of the bottom of the chute but yielding to permit the passage of coins on which said field has a predetermined effect.

6. In coin selecting mechanism, the combination of an inclined runway, an electro-magnet having its magnetic field disposed transversely of the runway between its ends, means for affording variation in the inclination of the runway, a yieldable trap door in the floor of the runway directly under the magnetic field, positively operating means for normally maintaining said door in the inclined plane of said floor, and means for varying the effect of said last recited means in accordance with variations in the inclination of the runway.

7. In coin selecting mechanism, the combination of a chute, a magnet for paramagnetic disks associated with one portion of said chute, an electro-magnet associated with another of said chute portions and having its magnetic field extending transversely across said portion, and a trap door in said last recited portions underlying the magnetic field.

8. In coin selecting mechanism, the combination of a coin chute comprising a plurality of portions, a magnet for paramagnetic disks associated with one of said portions, an off-chute from said chute portion adjacent said magnet, an electro-magnet associated with a second of said portions and having its magnetic field extending transversely across said portion, a trap door in said second portion underlying the magnetic field, and a chute extension of said second portion beyond said trap door.

9. In coin selecting mechanism, the combination of a coin chute comprising differently disposed portions, a magnet for paramagnetic disks associated with one of said portions, an off-chute from said portion adjacent said magnet, an electrode-magnet associated with a second of said portions and having its magnetic field extending transversely across said portion, a trap door in said second portion underlying the magnetic

- field, a chute extension of said second portion beyond said trap door, and a coin receptacle for rejected coins into which said chute extension and said off-chute both lead.
- 5 10. In a coin detector for check controlled mechanism, the combination of a coin chute comprising relatively settable portions, a permanent magnet associated with one of said portions, an off-chute from said chute 70
10 portion adjacent said permanent magnet, an electro-magnet associated with another of said portions and having its magnetic field extending transversely across said portion, a trap door in said last recited portion 75
15 underlying the magnetic field, a chute extension of said last named portion beyond said trap door, a rejection receptacle with which said chute extension and said off-chute both communicate, and a chute extension leading 20
20 from said trap door to the check controlled mechanism.
11. In a coin detector for check controlled mechanism, the combination of a runway, an electro-magnet having its magnetic field disposed transversely of the runway, a trap door 80
25 in the runway underlying the magnetic field and operative by coins on which the field has a certain effect, and a coin chute communicating with said trap door and connected with said check controlled mechanism.
12. In a fraud preventer, the combination of a runway, and an electro-magnet having its poles so arranged that the magnetic field is disposed transversely of the runway, the 90
30 floor of the runway having a yieldable portion directly beneath the magnetic field, said yieldable portion being normally in the plane of the floor and controlled by stop devices to prevent its movement above said plane but being yieldable to certain types only of coins affected by said field, and an adjustable weight for varying the operation of said door.
13. In a coin detector for check controlled mechanism, the combination of an inclined 100
40 coin chute, an electro-magnet having horizontally disposed pole devices projecting through the sides of said coin chute, said coin chute being mounted on said pole pieces, and means for affording variation in the inclination of said coin chute.
14. In a coin detector for check controlled mechanism, the combination of an inclined chute, an electro-magnet having horizontally disposed pole devices projecting through the sides of said coin chute, said coin chute and said pole pieces comprising a unitary structure, means for affording variation in the inclination of said coin chute, and a trap 110
50 door pivotally mounted on said coin chute and arranged in an opening in the bottom of said chute directly beneath said pole pieces.
15. In a coin detector for check controlled mechanism, the combination of an inclined 120
60 coin chute, an electro-magnet having horizontally disposed pole pieces projecting through the sides of said coin chute, said coin chute being mounted on said pole pieces, means for affording variation in the inclination of said coin chute, a trap door pivotally mounted on said coin chute and having its body portion arranged in an opening in the bottom of said chute directly beneath said pole pieces, said trap door having an off-set tail portion, and a weight adjustably mounted on said tail portion.
